CIRCUIT BREAKER

William H. Frank, Detroit, Mich., assignor to Bulldog Electric Products Company, Detroit, Mich., a corporation of West Virginia

Application November 8, 1941, Serial No. 418,419

16 Claims. (Cl. 200—116)

This application relates to circuit breakers. A principal object of the present invention is to provide a circuit breaker employing a single spring for providing all spring functions desired in a circuit breaker and wherein a novel interaction of operating parts of the circuit breaker is obtained through the relative positioning of the parts and the use of that single spring.

For an understanding of the circuit breaker herein disclosed, reference should be had to the appended drawings.

In these drawings:

Figs. 1, 2, and 3 show the device in closed circuit (on), open circuit (off), and overload released or "tripped" positions, respectively.

Fig. 4 is a plan view.

Fig. 5 is a section view.

Fig. 6 is a section view, with section lines omitted for the sake of clarity.

The circuit breaker herein disclosed comprises a two part or split casing 10 having a slot 11 in which moves a manually movable, hollow, open bottomed, contact support 12, pivotally mounted in recesses 13 on the sides of the casing by pivot lugs or stub shafts 14. Inner wall slots 15 of support 12, on its opposite sides and aligned with its lugs 14, mount a shaft 16 which is disposed in a hole 17 of a movable contact arm 18 having a contact 19 for engaging a stationary contact 20 mounted on a terminal connector.

A spring 21 has its upper end 22 simultaneously engaging edges 23a and 23b of lugs or arms 24a and 24b of the support and contact arm respectively, these defining an angle whose apex is designated "A", and which is spaced radially from either axis. The lower end of the spring seats in a notch of a block part 25 of the lower wall of the casing.

Integrally secured to the arm 18, near contact 19 and pivot 16 is a bimetallic strip or latch 26 connected by a flexible lead 27 to a terminal connector 28. The free end of the latch is bent to form a latching portion 29 cooperating with the support 12 for releasably interlatching the contact and the support at point 29. A sloping wall of the block 25 forms a stop 30 for the contact end of the contact arm. Ends 11a and 11b of slot 11 form eventual stops for support 12, and parts 20 and 30 are stops for arm 18.

Pin 31 in the portion 32 of the arm slidably engages the inner walls of the support for guiding the latching end of the arm with respect to the support.

Operation

"On."—In the closed circuit (on) position in-

5 dicated, (with latch holding), spring 21, disposed within the apex A formed by the meeting of the non-radial edges 23a—23b of lugs 24a—24b of the contact and support, biases both the contact and support to rotate in opposite rotative directions about their axes to maintain the support at rest in the closed circuit position, with end 11a of slot 11 of the upper wall of the casing eventually stopping the support; contact pressure is maintained at contact 19—20, with contact 20 stopping the arm 18. Support slots 15 permit movement of arm 18 against the spring force if the handle is forced too far.

"On" to "off."—Figs. 1 to 2: When the support 15 is moved manually to the position of Fig. 2, the contact arm moves with it to the open circuit position of Fig. 2. In the early part of the "on" to "off" stroke or circuit opening stroke, a compressive force is imparted against the spring 21; the line of action of spring 21, which had been to the left of the axes is swung to the right of the axes; after that line crosses the axes, the spring tends to relieve itself of part of the compressive stress and tends to snap the parts to the position of Fig. 2. Parts 30 and end 11b of the slot 11 form stops for the parts 18—20.

"Off" to "on."—Fig. 2 to Fig. 1: When the support 12 is swung from the position of Fig. 2 to Fig. 1, manually, the support and arm move as 30 a unit to swing the line of action of the spring from the right of the axes to the left thereof, first stressing that spring, and after the line of the spring crosses the axes, the spring relieves itself of part of its stress and snaps the contact arm to the closing position of Fig. 1. Parts 20, and end 11a of slot 11 provide stops for parts 18—12.

During manual actuation the support and arm move together as a unit, being pivotally connected at one point, and being interlatched at the other point.

"Overload release" or "trip."—Fig. 1 to Fig. 3: When the bimetallic 26 warps out from under the latching point of support 12, spring 21 biases the 45 contact arm to pivot relative to the support 12, to the open circuit position of Fig. 3. The handle or support need not move, and thus, even if held, will not interfere with free movement or tripping of the contact arm. Parts 30 and end 11a of slot 11 provide stops for parts 18—12.

"Relatch."—Fig. 3 to Fig. 2: For re-establishing the interlatched connection between the contact arm and the support it is merely necessary to rotate the support counterclockwise from the 50 position of Fig. 3 to that of Fig. 2 so that the

latching end of the support will catch up to the latching end of the contact arm and re-establish the interlatched connection between the parts. Contact arm 18 is held by stop 30 during relatching; stop 11b stops and holds the support after the handle has had sufficient overtravel for relatching.

Spring 21 imparts a biasing force simultaneously on the contact arm and the support at all times, and at all times tending to rotate them in opposite rotative directions, the support clockwise and the arm counterclockwise. This bias is inhibited, partially or wholly, by the various holds of the various parts. Thus, when the parts are in the closed circuit position of Fig. 1, with the latch holding, the holding effect of the interlatch at 28 prohibits relative movement of the arm and support, and spring 21 biases the support, and with it the contact arm, in the closed circuit position so that the net effect of the spring at that time is to establish and maintain contact pressure at 18-20.

When the holding effect of the latch disappears, as on overload, the bias of the spring is effective on the arm to cam it relative to the support, but is not effective to move the support, for the latter is held by the end 11a of slot 11.

When the parts are in the open circuit position, with the latch holding, the spring biases the contact arm against the stop 30 to hold the unit (arm and support) in such a way that the net effect of the spring is to maintain the parts in the open circuit position of Fig. 2.

It will also be observed that the apex A is radially spaced from the axes so that the pressure point of the spring on the contact arm and support is spaced radially from the axes to establish a moment arm for the contact arm and support about the axes.

The device here shown differs in principle from the device of the Morris and Lister Patent No. 1,071,566, Fig. 6, in that a single spring is used to provide all spring functions. The device hereof differs from the single spring device shown in a prior application of E. T. Platz, Serial No. 376,036, filed January 7, 1941, in that whereas the axes of rotation of the contact arm and support of the Platz device are spaced apart sufficiently to permit the arm to rock on one or the other of the spaced pivots, selectively, in my device, the axes of rotation are so located that the arm can not rock on either spaced pivot, selectively, but rather, the spring cams the arm and support simultaneously in opposite directions.

While the axes of rotation of the arm and support are shown as truly coincident, they need not be in coincidence, for a spacing of these axes, insufficient to permit the arm to rock selectively on the pivots, will not materially alter the mode of operation of the device here shown.

Now having described the device herein disclosed, reference should be had to the appended claims which determine the inventions hereof.

I claim:

1. In a circuit breaker, a manually actuatable contact support mounted for rotation about an axis, a contact arm pivotally mounted thereon to rotate with respect thereto about an axis of rotation, and having at a contact point thereof a movable contact portion, a stationary contact to be engaged thereby, means releasably interlatching the support and contact arm at a latching point, the axes being between the arm contact point and the interlatch point, and a single spring engaging the contact arm and the support simul- 75

taneously for biasing and indexing the support into and in its extreme positions, in one of which the contact arm contact is biased against the stationary contact for contact pressure, the spring also biasing the contact arm to move relative to the support on latch release for moving the contact thereof away from the stationary contact, the aforesaid axes being so spaced relative to each other that the arm cannot rock on either of the two pivots, selectively, the spring, when the parts are in closed circuit position, and interlatched, biasing the arm to its closed circuit position, and at the same time biasing the support to its closed circuit position, and when the latch releases, while still biasing the support to its closed circuit position, biasing the arm out of its closed circuit position.

2. In a circuit breaker, two pivoted members having portions extending in opposite radial directions from their pivotal axes, the portions defining sides of an angle whose apex is remote from the axes, and a spring means engaging such portions in the apex and thus biasing both said members in opposite rotative directions about the axes.

3. In a circuit breaker, two pivoted members having portions extending in opposite radial directions from their pivotal axes, the portions defining sides of an angle whose apex is remote from the axes, and a spring means engaging such portions in the apex and thus biasing both said members in opposite rotative directions about the axes, and means releasably interlatching said members so that they move as a unit when the latch holds, and move relatively when the latch releases.

4. In a circuit breaker, two pivoted members having portions extending in opposite radial directions from their pivotal axes, the portions defining sides of an angle whose apex is remote from the axes, and a spring means engaging such portions in the apex and thus biasing both said members in opposite rotative directions about the axes, one of the members having a stop portion, and a stationary abutment adapted to be engaged thereby for stopping the rotation of that member under spring bias, with the stopping point being radially spaced from the axis of that member.

5. In a circuit breaker, two pivoted members having portions extending in opposite radial directions from their pivotal axes, the portions defining sides of an angle whose apex is remote from the axes, and a spring means engaging such portions in the apex and thus biasing both said members in opposite rotative directions about the axes, one of the members having a contact portion, and a stationary contact adapted to be engaged thereby for stopping the rotation of that member under spring bias, the contact making point being radially spaced from the axis of that member.

6. In a circuit breaker, two pivoted members having portions extending in opposite radial directions from their pivotal axes, the portions defining sides of an angle whose apex is remote from the axes, and a spring means engaging such portions in the apex and thus biasing both said members in opposite rotative directions about the axes, one of the members having a stop portion, and a stationary abutment adapted to be engaged thereby for stopping the rotation of that member under spring bias, with the stopping point being radially spaced from the axis of that member, and means releasably interlatching

said members so that they move as a unit when the latch holds, and move relatively when the latch releases.

7. In a circuit breaker, two pivoted members having portions extending in opposite radial directions from their pivotal axes, the portions defining sides of an angle whose apex is remote from the axes, and a spring means engaging such portions in the apex and thus biasing both said members in opposite rotative directions about the axes, one of the members having a stop portion, and a stationary abutment adapted to be engaged thereby for stopping the rotation of that member under spring bias, with the stopping point being radially spaced from the axis of that member, and means releasably interlatching said members so that they move as a unit when the latch holds, and move relatively when the latch releases, with the interlatching point being radially spaced from the axes.

8. In a circuit breaker, two pivoted members having portions extending in opposite radial directions from their pivotal axes, the portions defining sides of an angle whose apex is remote from the axes, and a spring means engaging such portions in the apex and thus biasing both said members in opposite rotative directions about the axes, one of the members having a stop portion, and two stationary abutments spaced in the direction of travel thereof, and between which the member rotates, with the member adapted to be engaged thereby alternately for stopping the rotation of that member under spring bias in either direction.

9. In a circuit breaker, two pivoted members having portions extending in opposite radial directions from their pivotal axes, the portions defining sides of an angle whose apex is remote from the axes, and a spring means engaging such portions in the apex and thus biasing both said members in opposite rotative directions about the axes, each of the members having a stop portion, and two stationary abutments spaced in the direction of travel thereof, and between which the member rotates, with the member adapted to be engaged thereby alternately for stopping the rotation of that member under spring bias in either direction.

10. In a circuit breaker, two pivoted members having portions extending in opposite radial directions from their pivotal axes, the portions defining sides of an angle whose apex is remote from the axes, and a spring means engaging such portions in the apex and thus biasing both said members in opposite rotative directions about the axes, each of the members having a stop portion, and two stationary abutments spaced in the direction of travel thereof, and between which the member rotates, with the member adapted to be engaged thereby alternately for stopping the rotation of that member under spring bias in either direction, the stop portion of one of the members being formed as a contact portion, and one of the abutments therefor also being formed as a contact portion.

11. In a circuit breaker, two pivoted members having portions extending in opposite radial directions from their pivotal axes, the portions defining sides of an angle whose apex is remote from the axes, and a spring means engaging such portions in the apex and thus biasing both said members in opposite rotative directions about the axes, each of the members having a stop portion, and two stationary abutments spaced in the direction of travel thereof, and between which the

member rotates, with the member adapted to be engaged thereby alternately for stopping the rotation of that member under spring bias in either direction, the stop portion of one of the members being formed as a contact portion, and one of the abutments therefor also being formed as a contact portion, and means releasably interlatching said members so that they move as a unit when the latch holds, and move relatively when the latch releases.

12. In a circuit breaker, two pivoted members having portions extending in opposite radial directions from their pivotal axes, the portions defining sides of an angle whose apex is remote from the axes, and a spring means engaging such portions in the apex and thus biasing both said members in opposite rotative directions about the axes, each of the members having a stop portion, and two stationary abutments spaced in the direction of travel thereof, and between which the member rotates, with the member adapted to be engaged thereby alternately for stopping the rotation of that member under spring bias in either direction, the stop portion of one of the members being formed as a contact portion, and one of the abutments therefor also being formed as a contact portion, and means releasably interlatching said members so that they move as a unit when the latch holds, and move relatively when the latch releases, with the interlatching point being radially spaced from the axes.

13. In a circuit breaker, two pivoted members, one of which is a manually actuatable support, and the other of which is a contact arm, the members having portions extending in opposite radial directions from their axes defining sides of an angle whose apex is remote from the axes, and a spring means engaging such portions in the apex and biasing both said portions in opposite rotative directions about the axes, and means releasably interlatching said members so that they move as a unit when the latch holds, and move relatively when the latch releases, with the interlatching point being radially spaced from the axes, each of the members having a stop portion, and two stationary abutments spaced on opposite sides thereof, in the direction of travel thereof, and between which the member rotates, with the member adapted to be engaged thereby alternately for stopping the rotation of that member under spring bias in either direction, the stop portion of one of the members being formed as a contact portion, and one of the abutments therefor, also being formed as a contact portion.

14. In a circuit breaker, a manually actuatable contact support mounted for rotation about an axis, a contact arm pivotally mounted thereon to rotate with respect thereto about an axis of rotation, and having at a contact point thereof a movable contact portion, a stationary contact to be engaged thereby, means releasably interlatching the support and contact arm at a latching point, the axes being between the arm contact point and the interlatch point, and a single spring engaging the contact arm and the support simultaneously for biasing and indexing the support into and in its extreme positions, in one of which the contact arm contact is biased against the stationary contact for contact pressure, the spring also biasing the contact arm to move relative to the support on latch release for moving the contact thereof away from the stationary contact, the aforesaid axes being so spaced relative to each other that the arm can not rock on either of the two pivots, selectively, the spring,

when the parts are in closed circuit position, and interlatched, biasing the arm to its closed circuit position, and at the same time biasing the support to its closed circuit position, and when the latch releases, while still biasing the support to its closed circuit position, biasing the arm out of its closed circuit position, the axes being concentric.

15. In a circuit breaker, two pivoted members having portions extending in opposite radial directions from their pivotal axes, the portions defining sides of an angle whose apex is remote from the axes, and a spring means engaging such portions in the apex and thus biasing both said members in opposite rotative directions about the axes, the axes being concentric.

16. In a circuit breaker, two pivoted members, one of which is a manually actuatable support, and the other of which is a contact arm the members having portions extending in opposite radial directions from their axes, defining sides of an angle 20

whose apex is remote from the axes, and a spring means engaging such portions in the apex and biasing both said portions in opposite rotative directions about the axes, and means releasably interlatching said members so that they move as a unit when the latch holds, and move relatively when the latch releases, with the interlatching point being radially spaced from the axes, each of the members having a stop portion, and two stationary abutments spaced on opposite sides thereof, in the direction of travel thereof, and between which the member rotates, with the member adapted to be engaged thereby alternately for stopping the rotation of that member under spring bias in either direction, the stop portion of one of the members being formed as a contact portion, and one of the abutments therefore, also being formed as a contact portion the axes being concentric.

WILLIAM H. FRANK.
